 York, N. Y., a corporation of Delaware

Application November 3, 1945, Serial No. 626,477

13 Claims. (Cl. 92—71)

1

This invention relates to calender machines for treating web material such as paper.

Specifically, the invention deals with a tandem supercalender machine receiving web material successively through separate individual nips each defined by different rolls including swingably mounted rolls that can be replaced without stopping the machine.

Heretofore, supercalenders have consisted of a vertical stack of alternating hard chilled iron rolls and compressed fiber or "paper" rolls. The rolls in the vertical stack had to be maintained in exact vertical alignment, and any wear in the bearings for the rolls, permitting misalignment of the rolls, would result in uneven nip pressures along the lengths of the rolls. Complicated crowning contours for the rolls were also necessary to compensate for sagging of the rolls and for pressure on the roll bearings at the ends of the rolls. The web, such as paper, was passed through this stack type supercalender in a serpentine path to travel through the nips between adjacent rolls. Since the "paper" rolls were softer than the metal rolls, these rolls would become flattened and the paper web, passing around each paper roll, would be subjected to stretching action frequently resulting in tearing and bursting of the paper. The stretched paper would then tend to pile up at the next nip and the finish imparted to the paper at the previous nip would be destroyed. Any treatment given in a web in a conventional supercalender was, therefore, definitely limited to how much the web was stretched. In many instances, repeated treatment of the paper in a plurality of nips in a conventional supercalender, therefore, resulted in less finish on the paper than was obtained with only one pass through the first nip of the supercalender. In addition, any damage to the paper rolls of the conventional supercalender necessitated a complete stoppage of the machine to replace the damaged roll with a new roll.

The present invention now provides a supercalender machine composed of a plurality of nip-defining rolls arranged in tandem and successively receiving the paper web therethrough. The paper web is not lapped around a calender roll and is, therefore, not subjected to the repeated stretching action previously encountered in conventional supercalenders due to the flattening of the paper rolls. The tandem arrangement of nip-defining rolls makes possible the driving of successive rolls at any desired speed relative to the previous rolls, thereby accommo-

2

dating changes in length of the web and removing any limitation on web treatment due to stretching. If desired, the web can be moistened ahead of each succeeding nip without any limitation due to stretching of the sheet because the draw tension of the sheet between nips is easily controlled. The invention also provides an arrangement whereby damaged paper rolls can be quickly replaced without stopping the machine.

5 This arrangement includes a swingable mounting carrying a plurality of paper rolls including the active roll and a spare roll around a back-up roll that can be driven. The spare roll can be easily swung into active position while

10 being driven at the correct surface speed to replace the active roll, without stopping operations, whenever the active roll becomes damaged. The damaged active roll is swung to a convenient position where it can be replaced with a new

15 spare roll.

20 Since damaged paper rolls can be replaced without stopping the machine, this invention now makes it possible to use a supercalender at the end of a paper making machine to continually receive paper from the machine and to continually supply a supercalendered paper to a reel. Heretofore, supercalenders have not been directly attached to a paper machine since replacement of damaged paper rolls in the supercalender stack would necessitate stoppage of the entire paper machine.

25 The supercalender machines of this invention include a plurality of lower rigid driven rolls in spaced parallel relation. Each one of these rolls is driven by a prime mover such as an electric motor, or by any other drive arrangement which permits selective control of driving speeds. Each lower roll has a rigid pressure roll in spaced superimposed relation. A pair of paper rolls are 30 swingably mounted for rotation about the periphery of each pressure roll and can be selectively swung into pressure nip engagement with the lower roll. Controlled amounts of pressure are exerted on each pressure roll to provide the desired nip pressure between each lower roll and its cooperating active paper roll. The web material, such as paper, is passed successively 35 through the nips but does not lap around any of the paper rolls. The lower rolls are driven at speeds which maintain a desired tension on the web material and compensate for any stretching of the material as it passes through the previous nip.

40 It is, then, an object of this invention to provide a calender machine for web material hav-

45

50

55

ing a plurality of nips arranged in tandem and defined by independently controlled pairs of separate rolls.

A further object of the invention is to provide a tandem supercalender adapted to continuously receive paper direct from a paper machine and continuously feed supercalendered paper to a reel.

Another object of the invention is to provide a driven pressure applying roll arrangement for active and spare paper rolls of a calender machine which permits quick replacement of an active paper roll with a rotating spare roll driven at the correct speed for engaging a traveling web passing through the calender.

A still further object of this invention is to provide a supercalender having fiber or paper rolls which are not lapped by web material acted thereon and therefore cannot alternately stretch and release the web material even when the rolls are flattened under tremendous pressures.

A still further object of this invention is to provide a calender having an arrangement of active and spare calender rolls that decreases time of replacement of a damaged roll to a minimum.

A specific object of this invention is to provide a calender machine having a lower rigid roll, a pressure roll in spaced relation therefrom, and a plurality of calender rolls swingable around the periphery of the pressure roll to be selectively positioned in pressure nip relation with the lower roll.

Another object of this invention is to provide a supercalender having a plurality of nips which are independently controlled and operated.

Other and further objects of this invention will be apparent to those skilled in the art from the following detailed description of the annexed sheets of drawings which, by way of a preferred example only, illustrate one embodiment of the invention.

On the drawings:

Figure 1 is a side elevational view of a supercalender machine according to this invention, with parts omitted and with connecting parts for the omitted parts shown in vertical cross section.

Figure 2 is an enlarged fragmentary view similar to Figure 1 but illustrating the parts omitted from Figure 1.

Figure 3 is a fragmentary transverse cross-sectional view, with parts in end elevation, and with parts broken away, taken along the line III—III of Figure 1.

Figure 4 is a diagrammatic view illustrating operation of a conventional supercalender.

Figure 5 is a comparative diagrammatic view illustrating operation of a supercalender according to this invention.

As shown on the drawings:

The calender machine 10 includes a frame composed of pairs of front and rear upright columns 11 and front and rear top beams 12 supported by the columns. These columns and top beams provide spaces 13, 14 and 15 for the supercalender roll mechanism. The frames are mounted on a floor F and can vary to provide the desired number of spaces or operating stations to accommodate the desired number of roll mechanisms. While three such mechanisms have been shown, it should be understood that any number can be used, there preferably being at least two such mechanisms.

Each space 13, 14 and 15 has mounted therein a pair of roll-supporting frames 16 secured to the floor F. These frames 16 support bearing hous-

ings 17 rotatably carrying lower driven rolls 18. Each roll 18 is a rigid metal roll having a very hard, preferably chilled iron, peripheral surface.

As shown in Figure 3, each roll 18 is driven by an individual shaft 19 from an individual prime mover such as an electric motor (not shown), or a driver permitting independent control of the speed of each roll.

A doctor blade base support 20 is mounted between each pair of front and rear frames 16 and swingably carries a doctor blade 21 acting on the periphery of the adjacent lower roll 18.

The columns 11 have vertical tracks or ways 11a along the length thereof facing the spaces 13, 14 and 15. The tracks or ways 11a slidably support carriages 22. Threaded rods 23 depend through bosses on the top beams 12 into the spaces 13, 14 and 15 in front of the carriages 22. Nuts 24 cooperate with the top and bottom faces

20 of the bosses on the beams 12 to control the heights of the screw rods relative to the beams 12. Nuts 25 cooperate with the tops and bottoms of bosses on the carriages 22 and are threaded on the rods 23 to control the levels of the carriages 23 in the spaces 13, 14 and 15.

Pressure roll supporting arms 26 are pivoted on the carriages 22 and provide housings 27 for bearings 28 (Figure 3) rotatably supporting the axles of pressure rolls 29. A drive shaft 29a (Figure 3) is provided for each pressure roll so that these rolls can be driven independently at any desired speed.

As best shown in Figure 3, the bearing housing portions 27 of the arms 26 each have a cylindrical flange portion 27a surrounding an axle of the pressure roll 29 and rotatably supporting a surrounding bracket 30. Each bracket 30 has diametrically opposed outwardly projecting portions carrying split bearing clamps 31 at their outer ends. Each bearing clamp 31 includes pivoted-together clamping jaws adapted to be tightly clamped around an inserted bearing by means of clamping nut and bolt assemblies as shown.

The split bearing clamps 31 are arranged so that the pressure roll 29 can act directly on a roll carried by the clamp without interference from the bracket 30. Thus, the clamps float on a bracket 30 and are each composed of a clamp arm 31a pivoted on a pin 32 carried by the bracket 30 and an arm 31b pivoted to the free end of the arm 31a by means of a pin 33. This pin 33, in turn, is carried by a boss 34 on a rod 35 which is pivoted to the bracket 30 as at 36. Nuts 37 are threaded on the rod 35 to hold the boss 34 outwardly from the bracket 30. A rubber block 38 on the rod 35 abuts the other end of the boss 34 and is held on the rod by means of a nut 39. A swing bolt 40 is pivoted to an ear provided on the bracket 30 by means of a pin 41 and a nut 42 threaded on the swing bolt 40 thrusts against a pointed washer member 43 on the bolt to draw the free end of the clamp arm 31b toward the pin 41.

Calendar rolls 44 having compressed fiber or paper covered peripheries have laterally projecting axles 44a with bearings 45 mounted on the ends thereof. These bearings 45 are seated in the split bearing clamps 31 and are held therein against axial and rotational movement. The axles 44a rotate in the bearings 45. A pair of rolls 44 are thus rotatably mounted on diametrically opposed sides of the pressure roll 29 in peripheral engagement therewith and driven thereby at the correct speed and to engage the traveling web being treated in the machine. The rolls 44 are

65 70 75 76

removably retained by the clamps 31 on the brackets 30 which can swing around the circular flanges 27a of the bearing housings 27.

A ring gear 46 is bolted on each bracket 30 and surrounds the bearing flange 27a. Gears 47 on shafts 48 carried by the arms 26 mesh with the gears 46. Additional gears 49 are secured to the shafts 48 outside of the arms 26 and mesh with gears 50 on a cross shaft 51 carried by the arms 26. A sprocket 52 is keyed to the shaft 51 and is driven by a chain 53 from a motor-driven sprocket 54. The sprocket 54 is driven by an electric motor 55 in a casing 56 carried by the rear arm 26. The motor is preferably equipped with an electric brake which will lock the sprocket chain 53 against movement whenever the motor is deenergized. Energization of the motor 55 will drive the sprocket chain 53 to rotate the shaft 51 thereby rotating the shafts 48 through the meshed gears 50 and 49. The rotating shafts 48 will drive the gears 47 to rotate the ring gears 46 and thereby swing the brackets 30 around the circular flanges 27a of the bearing housings 27. This will swing the calender rolls 44 around the pressure roll 29 to selectively move the calender rolls 44 into the space between the lower roll 18 and the pressure roll 29.

The split bearing caps 31, being on diametrically opposite sides of the pressure roll 29, will position a roll 44 on top of the roll 29 whenever the other roll 44 is in the space between the rolls 18 and 29. The bearing caps are quickly opened so that the roll 44 on top of the roll 29 can be removed and replaced with a new roll. The roll 44 on the top of the roll 29 is a spare roll which is quickly shifted into operative position with the lower roll 18 upon energization of the motor 55. Each calender roll 44 preferably has a doctor blade 57 acting thereon to keep the periphery thereof in a clean condition. The doctor blades 57 are mounted on swingable carriages supported from bosses 58 on the arms 26.

Pressure applying arms 59 are pivoted on the carriages 22 above the arms 26. These arms 59 are preferably curved to be placed above the spare rolls 44 on top of the rolls 29. The free end of each arm 59 is coupled to a threaded rod 60. Each threaded rod 60 depends from a worm and gear casing 61 pivoted to a bracket B on top of the top beam 12. Motors M drive the worms (not shown) in the casings 61 to rotate the gears (not shown) in the casings. Since each rod 60 is threaded through a gear in a casing 61, the motors M will raise and lower the rods 60 and thereby swing the arms. A motor M is preferably coupled to the worm in casings 61 on the front and rear sides of the frame so that both rods 60 for the arms 59 of a calender assembly will be actuated together.

A coil spring 62 is positioned between each pressure roll carrying arm 26 and its pressure arm 59 so that downward pressure exerted on the pressure arm 59 will compress the spring 62 to load the roll-carrying arms 26 and thereby place the bottom or active calender roll 44 into pressure nip relation with the lower roll 18. A link 63 ties the free ends of the arms 26 and 59 together so that the rods 60 may be rotated to raise the arms 59 and carry the arms 26 therewith through the links 63. However, the links 63 have a lost motion connection with the arms 26 so that the pressure exerted on the spring 62 will be transmitted to the arms 26 and pressure roll 29. Thus the lower ends of the links 63 have elongated slots 63a therein receiving pins 64 on the free ends of the arms 26. When the arms 59 raise the links 75

63 sufficiently, the pin 64 will be engaged by the bottoms of the slots 63a and the arms 26 will be swung upwardly to move the pressure roll 29 and lower calender roll 44 away from the lower roll 18. Conversely, when the screw rods 60 are actuated to force the arms 59 downwardly, the lower calender roll 44 will engage the roll 18 to limit further downward movement thereof and pressure of the springs 62 when compressed by the arms 59 will be transferred to the arms 26, roll 29, and lower calender roll 44. The floating bearing caps 31 will permit the roll 29 to press on the periphery of the lower roll 44 and urge the periphery of this roll toward the roll 18 without interference, since the rubber washers 38 provided in each floating bearing cap will be deformed to permit relative movement between the bearing cap and the supporting arm 26. In this manner, the roll 29 acts as a pressure roll or backing up roll for the active calender roll 44 and engages the active calender roll 44 along the entire length thereof to create an even nip pressure between the roll 18 and lower roll 44.

As best shown in Figure 1, a guide roll 65 is mounted adjacent each lower roll 18 and a paper web W passes under each guide roll and thence over the top portion of the lower roll 18. The guide rolls thus cause the paper web W to partially lap around the lower rolls 18 and travel on these rolls through the nip of each supercalender assembly. The guide rolls 65 are preferably hollow to receive heating or cooling fluid therethrough for adjusting the temperature of the web W before it passes through the succeeding nip. Thus, if desired, coolant can be flowed through the hollow guide rolls 65 to cool the paper or other web material and thereby aid in maintaining a cool nip temperature. Conversely, steam or other heating fluid can be flowed through the hollow guide rolls 65 to heat the web before it passes through the nips.

Shower pipes 66 extend transversely across the top and bottom faces of the web W in spaced relation therefrom, and are arranged to eject jets of steam, water, or the like for treating the web before it passes through the nips of the supercalender. In many instances it is desirable to moisten the web so that a wet surface will be acted on by the nip of the supercalender.

The web W can be received into the first supercalender directly from the drier section of a paper machine and will pass under the first guide roll 65 and thence through the first nip provided by the first supercalender assembly. The web will then pass in succession through the nips of the succeeding supercalender assemblies and will lastly pass under a guide roll 67 en route to a reel or winding apparatus. Any stretching of the web due to the pressure nip treatments is accommodated by driving the successive rolls faster to maintain a desired draw tension on the web. Of course, it should be understood that the supercalender machines of this invention can be used as finishing room equipment and receive web material from a wound roll instead of directly from the paper machine. The supercalender machine, however, can handle continuously moving web material directly from a paper machine to continuously supply a reel or winder with finished paper. If, during the operation of the calender machine, any one of the pressure roll-driven active fiber rolls 44 becomes damaged, it is merely necessary to operate a motor M for raising the roll 44 out of pressure engagement with the lower roll 18 and

then operate the motor 55 for swinging the pressure roll driven spare roll into active position. The motor M is next operated in the reverse direction to place the spare roll into active pressure relation with the lower roll 18. This replacement of a damaged roll thus only requires a very short time and the movement of the web material is not interfered with during the changeover. Since the other calender assemblies will still be active during the changeover of one of the assemblies, a finished web surface will be maintained.

In the diagrammatic showing of Figure 4, there is illustrated a conventional calender stack composed of alternating hard surfaced rolls 18' and fiber surfaced or paper rolls 44' in superimposed vertical alignment. A paper web W' enters from the top of the stack and emerges from the bottom of the stack after passing around the rolls in a serpentine path. Under the high pressures of a supercalender, the fiber rolls or paper rolls 44' will be flattened or depressed at the nips. One fiber roll 44' cooperates with two adjacent hard surfaced rolls to provide two nips successively receiving the paper web. The radii of the rolls at the nip points are designated by the reference characters R. However, the portion of the rolls 44' not subjected to the nip pressure will have a longer radius R' so that the peripheral speed of each roll 44' is slower at the nips thereof than at the portion thereof spaced from the nips. Now the web of paper W' successively passes between both nips of each roll 44' and is lapped around the roll between the nips. The differences in peripheral speeds of the rolls 44' caused by the difference in radii R and R' places a tremendous tensile strain on the web W' at each nip. Thus the web W' is held at a relatively slow speed in the first nip, and is then stretched as it passes around the roll 44'. The roll, of course, will slip somewhat relative to the web but, since the web must lie tightly on the roll to obtain a good finish therefrom, a tremendous strain is placed on the web. The fast-moving web around the radius portion R' of the roll is then slowed up at the next nip where the radius is decreased to R and the tension is removed on the web and, if stretched, it tends to pile up at this next nip. From this analysis of the conventional calender stack, it will be seen that considerable operating difficulties are encountered and the paper web is subjected to alternately stretching and piling up conditions which interfere with production of a uniform finished surface on the paper. It will also be seen that replacement of a damaged fiber or paper roll 44' in a vertical stack is quite difficult and requires stoppage of operation.

In the diagrammatic view of Figure 5 the supercalender assembly of this invention is illustrated, from which it will be noted that the web W does not lap around the flattened fiber or paper roll 44 and is therefore not subjected to the stretching and piling up conditions met by the web W' in the conventional calender stack. The web W only laps the lower roll 18 and is carried thereby through the single nip of the assembly. Since, of course, the assembly is followed in tandem with other assemblies of the same type, the web can receive as many nip treatments as in a vertical stack and never be subjected to the undesirable conditions encountered in a vertical stack.

The flattened conditions of the rolls 44 and 44' in the diagrammatic views of Figures 4 and 5

are somewhat exaggerated beyond actual operating conditions, but the diagrammatic views are merely for the purpose of illustrating the conditions that actually are encountered in operation of the conventional supercalender stack of rolls and the supercalender assembly of this invention.

It will, of course, be understood that various details of construction may be varied through a wide range without departing from the principles of this invention and it is, therefore, not the purpose to limit the patent granted hereon otherwise than necessitated by the scope of the appended claims.

15 I claim as my invention:

1. A calender machine adapted for treating paper comprising a first roll, fixed bearings rotatably supporting said first roll, a drive for said first roll, upright supports adjacent said first roll, carriages shiftably mounted on said upright supports, roll-carrying arms pivoted on said carriages, a pressure-applying roll rotatably carried by said arms, pressure-applying arms pivoted on said carriages above said roll-carrying arms, compression springs between the pressure-applying arms and roll-carrying arms, means for swinging said pressure-applying arms to compress said springs for loading said roll-carrying arms, and a plurality of calender rolls swingably mounted around the periphery of said pressure-applying roll for selective shifting into operative relation with the first roll whereby pressure applied to said roll-carrying arms will be transmitted through the pressure-applying roll and active calender roll to create a pressure nip between the active calender roll and the first roll.

2. A calender machine adapted for treating paper comprising a first roll, fixed bearings rotatably supporting said first roll, a pressure roll, bearings rotatably supporting said pressure roll, shiftable housings carrying said bearings, cylindrical flanges on said housings, brackets rotatably mounted on said flanges, a plurality of split bearing clamps carried by each bracket, a plurality of calender rollers having bearings removably clamped in said split bearing clamps, yieldable means accommodating swinging movement of the split bearing clamps relative to said brackets, means for rotating said brackets around the cylindrical flanges of said bearing housings to selectively position the rollers into nip-defining relation with the first roll, and pressure means for loading the bearings for the pressure-applying roll to urge said pressure-applying roll toward said first roll and thereby maintain a roller in pressure nip relation with the first roll.

3. In a pressure roll assembly adapted for treating paper, a first roll, a pressure-applying roll spaced from said first roll, means for shifting said pressure-applying roll toward and away from said first roll, a plurality of rollers swingably mounted around the periphery of said pressure-applying roll, split bearing clamps mounting said rollers relative to the pressure-applying roll, and yieldable means accommodating movement of said split bearing clamps relative to the pressure-applying roll whereby pressure exerted on the pressure-applying roll will be transferred through the periphery of the roll to the periphery of the rollers for creating a nip pressure between a roller and the first roll.

4. In a pressure roll assembly adapted for treating paper, a pair of opposed bearing hous-

ings having cylindrical mounting portions, bearings in said housings, a pressure roll rotatably carried by said bearings, brackets rotatably mounted around said cylindrical portions of the bearing housings, a plurality of bearing clamps carried by each bracket, each bearing clamp having a first clamping jaw pivoted to the bracket, a second clamping jaw pivoted to the first clamping jaw, clamping means for drawing the jaws together, and yielding means connecting the pivot between the jaws with the bracket, a plurality of rollers rotatably supported around the periphery of said pressure roll by said bearing clamps, and means for simultaneously rotating said brackets to selectively shift the rollers into and out of active position.

5. A calender machine adapted for treating paper comprising a plurality of rolls arranged in spaced tandem relation, a frame having upright columns adjacent each of said rolls, carriages movable on said columns, means on said frame for raising and lowering said carriages, roll-carrying arms pivoted on said carriages, pressure rolls rotatably carried by said roll-carrying arms, pressure-applying arms pivoted on said carriages above said roll-carrying arms, compression springs between the pressure-applying arms and roll-carrying arms, links connecting the pressure-applying arms and the roll-carrying arms and accommodating limited relative movement between the arms, means on said frame for swinging the pressure-applying arms to load said springs and to raise the links for raising the roll-carrying arms, brackets rotatable about the axis of said pressure rolls and supported by said roll-carrying arms, a plurality of calender rolls rotatably mounted in said brackets and including an active calender roll in pressure nip relation with each tandem roll and a spare calender roll on the opposite side of the pressure roll, and means for shifting said brackets to move the spare calender rolls into operative position with the tandem rolls.

6. In a paper calendering machine, a frame, a roll journaled in said frame for rotation about a fixed axis, means for driving said roll by power, a pressure roll spaced from said first-mentioned roll, bearing support means for said pressure roll mounted on said frame for adjustable movement toward and from said first roll, means for adjustably moving said bearing support means and pressure roll toward and from said first roll, spaced bracket members mounted adjacent opposite ends of said pressure roll for adjustable movement about the axis thereof, bearing members mounted in said brackets for movement toward and from said pressure roll, a plurality of calender rolls journaled in said bearing members, power means for adjustably moving said bracket members about the axis of said pressure roll to selectively position said calender rolls between said pressure roll and said first roll to cooperate with said first roll and provide a calender nip therebetween, and means cooperating with said means for adjustably moving said pressure roll toward and from said first roll, including yielding means urging said pressure roll toward said first roll and yieldably engaging said calender roll with said first roll, and means for rotatably driving said pressure roll.

7. In a paper calendering machine, a frame, a roll journaled in said frame for rotation about a fixed axis, means for driving said roll by power, a pressure roll journaled in said frame, bearing support means for said pressure roll mounted for

adjustable movement toward and from said first roll, means for adjustably moving said bearing support means toward and from said first roll including means yieldably urging said pressure

5 roll toward said first roll, spaced bracket members mounted adjacent opposite ends of said pressure roll for adjustable movement about the axis thereof, bearing clamps pivotally mounted in said bracket members for movement about axes parallel to the axis of rotation of said bracket members, means for restraining pivotal movement of said bearing clamps, bearing members mounted in said bearing clamps for ready removal therefrom, a plurality of calender rolls journaled in said bearing members, means for adjustably moving said bracket members about the axis of said pressure roll to selectively position said calender rolls between said pressure roll and said first roll, to cooperate with said first

20 roll and provide a calender nip therebetween, and means for driving said calender roll at the peripheral speed of said first roll, comprising means for rotatably driving said pressure roll.

8. A calender machine adapted for treating a paper web comprising a first rigid roll mounted for rotation about a fixed axis, a second rigid roll in spaced relation from said first roll and mounted for rotation about a shiftable axis, a plurality of calender rolls, two laterally spaced brackets mounted for rotation about the axis of said second roll, bearings for said calender rolls, support members for said bearings pivoted to said brackets for movement about axes offset from the center thereof, yieldable means restraining pivotal movement of said support members, means for swinging said calender rolls to selectively position one of the calender rolls between the first and second rolls, and means for applying pressure on the ground roll to create

40 a pressure nip between the first roll and the adjacent calender roll.

9. A calender machine adapted for treating paper comprising a first roll, fixed bearings rotatably supporting said first roll, a second roll, shiftable bearings rotatably supporting said second roll, support means for said bearings, means for shifting said support means and bearings and moving said second roll toward and from said first roll, rotatable brackets pivotally mounted adjacent opposite ends of said second roll for movement about the axis thereof, a plurality of spaced calender rolls journaled on said brackets for movement about said second roll to position one of said calender rolls between said first and second rolls, the means for journaling said calender rolls on said brackets including detachable bearing supports, means for mounting said bearing supports for movement toward and from said second roll, yielding means restraining movement of said bearing supports, and means for adjustably moving said brackets about the axis of said second roll and thereby selectively positioning one of said calender rolls between said first and second rolls to cooperate with said first roll and provide a calender nip.

10. A roll assembly adapted for treating paper comprising a driven roll, a pressure-applying roll in spaced relation from said driven roll, means for shifting said pressure-applying roll toward and away from said driven roll, brackets rotatably mounted around the axis of said pressure-applying roll, roller-supporting bearing clamps pivotally connected to opposite ends of said brackets for movement with respect thereto about axes offset from the centers thereof, means yield-

11

ably restraining movement of said clamps, calender rolls detachably journaled in said clamps, and means for pivotally moving said brackets and moving said calender rolls about the periphery of said pressure-applying roll to selectively position a calender roll in nip relation with said driven roll and pressure-applying roll.

11. A calender machine for calendering paper comprising a hard surfaced roll, a drive for said roll, means for lapsing a paper web partially around said roll to be driven thereby, a pressure-applying roll spaced from said roll, a drive for said pressure-applying roll, a bracket adjacent each end of said pressure-applying roll journaled for rotation about the axis of said pressure applying roll, each bracket having portions extending radially beyond the periphery of said pressure-applying roll at circumferentially spaced apart points of said periphery, quick opening bearing clamps on said extending portions of said brackets, paper rolls releasably journaled in said bearing clamps, means mounting said bearing clamps on said brackets for movement of said paper rolls toward and away from the periphery of said pressure-applying roll, means for swinging said brackets to move a spare paper roll around said pressure-applying roll into position between said pressure-applying and driven rolls, and means for loading the pressure-applying roll to press a paper roll between said pressure applying and driven rolls.

12. In a paper calendering machine, a first roll journaled for rotation about a fixed horizontal axis, power means for driving said first roll, a pressure roll spaced above said first roll in parallel horizontal relation with respect thereto, vertically adjustable support means for said pressure roll, means for adjustably moving said support means toward and from said first roll, bracket members mounted adjacent opposite ends of said pressure roll for rotatable movement about the axis thereof, said bracket members each having portions extending beyond the periphery of said pressure roll at circumferentially spaced points, roll bearing supports movably carried by said brackets, pairs of said roll bearing supports being aligned at opposite ends of the pressure rolls, a calender roll journaled for rotation in each pair of said roll bearing supports and movable therewith toward and away from the periphery of said pressure roll, and means selectively operable to rotatably move said brackets about the axis of said pressure roll to selectively position a calender roll between said first roll and said pressure roll to cooperate therewith for forming two calender nips.

13. In a paper calendering machine, a first roll journaled for rotation, power means for driv-

12

ing said first roll, a pressure roll spaced from said first roll, bearing support means for said pressure roll, means for adjustably moving said bearing support means and pressure roll toward and away from said first roll, spaced bracket members mounted adjacent opposite ends of said pressure roll for adjustable movement about the axis thereof, said bracket members having portions extending beyond the periphery of said pressure roll at a plurality of circumferentially spaced points on said pressure roll, bearing supports pivotally mounted on said brackets adjacent the outer ends thereof for movement about axes parallel to the axis of rotation of said pressure roll, said bearing supports being movable toward and away from said pressure roll, means restraining said movement of said bearing supports, a plurality of calender rolls journaled in said bearing supports, power means for adjustably swinging said bracket members about the axis of said pressure roll to selectively position said calender rolls between said first roll and said pressure roll to cooperate with said rolls and provide two calender nips, and means cooperating with said means for adjustably moving said pressure roll toward said first roll for urging said pressure roll toward said first roll and exerting a predetermined pressure on said calender roll therebetween.

CHARLES P. PUTNAM.
